UNITED STATES PATENT OFFICE.

GEORGE EUGENE MITTINGER, OF CLEVELAND, OHIO.

METALLIC HEAD FOR WOODEN KEGS AND THE LIKE.

Application filed January 25, 1924. Serial No. 688,431.

To all whom it may concern:

Be it known that I, GEORGE E. MITTINGER, a citizen of the United States, residing at Cleveland, in the county of Cuyahoga and 5 State of Ohio, have invented certain new and useful Improvements in Metallic Heads for Wooden Kegs and the like, of which the following is a specification, reference being had therein to the accompanying 10 drawing.

This invention relates to improvements in metallic heads for wooden kegs and the like and it is intended specially for kegs that are packed with nails, nuts, rivets, etc.

15 Wooden kegs with wood heads which are made to receive nails, nuts, rivets, etc., for shipping, must be made cheap, and necessarily the material and labor are cheap, which makes the heads liable to be forced 20 out under the weight of the contents, or the kegs to collapse in the rough usage of transportation and otherwise to which they are necessarily subjected.

25 In providing a metallic head for a wooden keg it is essential that the head be attached to the wooden keg so that it can not be detached by rough usage to which the keg is subjected in the handling of it in being transported from the manufacturer to its 30 destination.

It is well known to those handling wooden kegs packed with nails, nuts, rivets, bolts, etc., that the heads are frequently forced 35 out by the weight of its contents when the keg is accidentally dropped, or the keg collapses with the result that its contents are lost or must be swept up, and as a consequence they must to a certain degree be 40 carefully handled to prevent such occurrence.

Bearing in mind the foregoing weakness 45 of wooden kegs, the primary object of my present invention is the production of a metallic head which when applied will prevent the keg from collapsing, and will prevent the removal of the head by the dropping of the keg, while at the same time is capable of being quickly removed when it is desired to be opened, all of which will be 50 understood from the following description and disclosure.

In the accompanying drawings:

Figure 1 shows a sectional view of one 55 end of a wooden keg with my improved metallic head applied thereto.

Figure 2 is a similar view, with my im-

proved metallic head in position to be expanded for engaging the croze of the keg.

Figure 3 is a view showing the manner of quickly and readily detaching the head when 60 it is to be removed.

Figure 4 is a top plan view showing somewhat the roughness of a cheap wooden keg, to which my improved metallic head is applied. 65

Figure 5 is a sectional view on the line 5-5 of Figure 1.

Figure 6 is a side elevation of a wooden keg with the wooden head, which shows the manner of constructing the wooden keg upon 70 which the present invention is an improvement.

Figure 7 is a top plan view of the wooden keg with the wood head.

In the drawings: the wooden keg 1 has 75 the ends of its staves 2 cut away as shown at 2' and immediately below the cut away portion it is provided with an annular groove 3 usually referred to as the croze. All wooden kegs and the like are constructed as above described as is well known. The keg to which my improved metal cover 4 is attached, is made up of very rough material, the said material not being planed at all, and the staves having their edges 80 shaped so as to make the bilged portion 5 of the keg. When the staves are secured together by the bands 6 their ends are in irregular form as shown in Figure 4.

My improved cover 4 is stamped or 90 pressed from sheet metal and has a centrally flat portion 7, and a peripheral upwardly and outwardly inclined part 8, an annular flat portion 9 and a downwardly and outwardly extending part 10. The parts 8 and 95 10 are inclined to correspond with the inside cut away portion 2' of the stave and with the taper of the outer side of the stave due to its bilge. Preferably the lower edge of the inclined outer wall 10 is double at 100 11 which strengthens the cover as will be understood.

With the cover in the shape described it is adapted to fit the upper ends of the staves, so that by applying the cover at one 105 edge of the keg inclined upward and then forcing downward its high end gradually forces inward the irregular staves 4 (as shown in Fig. 4) until they are nested in proper circular form in the cover as shown 110 in Figure 5.

Having thus placed the cover 4 in posi-

tion on the end of the wooden staves it is secured in that position by expanding it inward into the croze 3 as shown at 12. The expansion of the cover lifts up the flat portion 7 until the flat portion is about on a level with the lower edge of the croze. That is to say, when the cover is in position to be expanded into the croze 3 the flat portion 7 is below the croze as shown 10 in Figure 4, whereas the expansion of the part 8 lifts the flat portion 7 until it is about on a line with the lower part of the croze.

This operation clamps the ends of the 15 staves between the expanded portion 12 and the inclined portion 10, thus making secure covers for the ends of the keg. This cover is so tightly clamped to the ends of the staves of the keg that it can not be 20 forced outward by the impact of its contents if the keg should be dropped, in the handling of it, even a considerable distance. Therefore this covering is unquestionably 25 substantially permanent for holding the contents in the wooden keg. Attention is directed to the fact that the flattened portion 11 is preferably slightly above or substantially opposite the croze of the keg thereby providing the cover with a stiffening 30 to sustain the outer tension caused by pressing the cover into the croze. This arrangement produces a very tight clamp and one which will stand the very rough usage 35 to which the keg in transportation is at times subjected.

Having produced a cover which is clamped so tightly to the ends of the staves, the next problem was to devise means for removing the cover when it is desired to 40 open it for access to its contents. I accomplish this in the following manner: When the keg has reached its destination and it is desired to remove the cover, the cover is knocked down as shown in Figure 3 by 45 means of a hammer, hitting it around its edge as shown at 13, Figure 3, which draws the expanded portion 12 out of the croze when the cover can be removed. The material of which the cover is made is pliable 50 and simply tapping it on the outer side draws the cover out of the croze. With the cover expanded into the croze as at 12 in Figure 1 any outward pressure of the contents serve to force the expanded portion 55 tighter in the croze, but by tapping it downward readily draws it out of the croze so that it is quickly and readily removed. It is surprising how quickly and readily the cover can be removed and it requires only 60 a very few seconds to accomplish it.

A much better grade of wood is required for heads than for staves, and manufacturers of wooden kegs find that suitable heading material is very scarce and have

for a long time been seeking some means to 65 take its place.

I am aware that many efforts have been made to produce a metallic covering for wooden kegs. In some instances the keg has been provided with an outside croze 70 and the cover has enclosed the ends of the staves and the outer wall contracted into the croze at the outer side of the keg. In the first place it has been found impractical to contract the metal in this outer croze, 75 and in the second place no practical means has been devised to remove the contracted portion from the croze. In fact attempts have been made to use this construction and it has been found wholly unsuited. An 80 other effort has been made to hold the cover in by friction only but this has been found impractical since the contents would force the cover out of the end of the keg. Many other attempts have been made, but so far 85 as I am aware I am the first to expand the inner wall into the croze which makes a very tight strong connection of the cover with the keg, and I am the first to discover how to remove the cover by bending it 90 down with blows to cause the expanded portion to be removed from the croze in which it extends. It will be understood that a keg packed with nuts, rivets, bolts or nails are sufficiently loose to enable the 95 cover to be removed in the manner explained. My improvement has been shown to large manufacturers of wooden kegs and they have declared it to be a solution of the problem and have given me large orders 100 for it, although they have been aware of these previous attempts to solve the problem.

Attention is directed to the fact that in my improved cover before its inner upwardly extending wall is expanded into the croze, the flat portion 7 is below the outer part 10. This arrangement is convenient and useful in placing the cover on the end of the keg in the inclined manner previously explained. It enables me to perform the operation which will cause the cover as it is gradually pushed downward to squeeze the ends of the staves into tight and proper position. When the expansion is completed, the finished head as the surrounding ring or flange 11 is slightly below or substantially opposite the expanded part 12 for the purpose previously stated.

My improved metal cover is quite a saving in the cost of the material as well as labor over the ordinary wood cover. In a wood cover it is necessary to furnish a band of metal 14 which is applied to the end of the keg after the wood head is placed in position. This metal band requires the cost 120 of the metal, the cost of putting in the two rivets 15 to attach the ends of the bands, and the cost of the nails 16, and the time 125

required to apply the nails. The driving in of the nails is guess work, sometimes being improperly performed, which fails to properly secure the head in position. Furthermore when the kegs are to be exported with the wooden heads, it is necessary to provide a band 17 which is nailed to the sides of the barrel and extends across the head, and is nailed to the head as shown at 18. With my improved head all of this is not required.

From the foregoing description it will be understood that the invention is adapted for barrels as well as kegs, and I desire it understood that slight modifications may be made in the specific construction without departing from my present invention so long as the modifications are within the scope of the appended claims.

Having thus described my invention what I desire to claim and secure by Letters Patent is:

1. The improved process of applying a metal cover to a keg, which consists in providing a keg with an annular groove in its inner side adjacent one end, providing a

metal cover with an inverted U-shaped periphery with its inner wall substantially straight, applying the said cover to the end of the keg, and then expanding the inner vertical wall outward into the said annular groove and thus tightly clamping the head to the keg.

2. The process of attaching and removing a metallic head to and from a keg, which consists in providing a keg having an annular groove located at its inner side near one end, providing a metallic head having a substantially U-shaped periphery, the inner wall of said U-shape being substantially straight, applying the said metal head to the end of the keg, then expanding the vertical portion of the U-shape into the annular groove, and removing the head from the keg by forcibly depressing the horizontal portion of the head thereby withdrawing the expanded portion from the said annular groove, whereby the head is readily removed.

In testimony whereof I hereunto affix my signature.

GEORGE EUGENE MITTINGER.
